UNITED STATES PATENT OFFICE.

SIMEON F. PIERCE, OF ST. PAUL, MINNESOTA.

GENERATING APPARATUS.

1,107,836.

Specification of Letters Patent. Patented Aug. 18, 1914.

Application filed July 14, 1913. Serial No. 778,971.

To all whom it may concern:

Be it known that I, SIMEON F. PIERCE, a citizen of the United States, residing at St. Paul, in the county of Ramsey and State of Minnesota, have invented certain new and useful Improvements in Generating Apparatus, of which the following is a specification.

My invention relates to improvements in generators for generating gas from heavy hydro-carbon liquids as kerosene, its object being particularly to provide a construction in which the parts are kept effectively cleaned of carbon deposits, thus allowing heavy hydro-carbon liquids to be used with the same effectiveness as the lighter liquids, as gasolene, are used in the ordinary constructions.

To this end my invention includes means for passing the main body of liquid hydro-carbon being used in the apparatus, through the generating parts at predetermined times to cause a thorough cleaning of the same.

My features of invention while shown applied to a stove and light are equally well applicable to other analogous constructions, where a generating burner is used as blow torches, etc.

In the accompanying drawings forming part of this specification, Figure 1 is a side elevation, broken away, of a stove and light embodying my features of invention; Fig. 2 is a front elevation of the same broken away; Fig. 3 is a detail of a generator shown partly in section; and Fig. 4 is a section on line $\alpha-\alpha$ of Fig. 3.

Referring to the drawings, A represents the framework of a stove.

B represents burners of suitable construction supported upon the ends of branch gas pipes 2, each pipe at its connection with the burner being provided with a suitable controlling valve 3. The gas pipes 2 are connected through the generator C with a pipe 4 leading from the bottom of the oil reservoir D. A controlling valve 5, as shown, is arranged in connection with the pipe 4 a short distance from the generator. The generator, as shown particularly in Fig. 3, includes a central mixing tube 6 open at its bottom to the outer air, a jet orifice 7 being formed in the generator below the bottom of the mixing tube, a needle valve 8 having screw threaded support in connection with the jet orifice.

The generator chamber 9 is connected by a downwardly and laterally extending conduit 10 with a second generating chamber 11, extending around the mixing tube below the generating chamber 9. The lower generating chamber 11 is connected at its lower side by a conduit 12 with the jet orifice, the conduit 12 extending past the jet orifice to a tube 13 connected with the bottom of a filling tank E supported upon the rear of the stove. The inlet tube 4 is preferably filled with loose parts 14, as shot, for the purpose of pulverizing the hard carbon in the fluid supply.

As shown, the mixing tube extends some distance above the generator 9, the generator being formed with an outer open top tube 15 surrounding the upper end of the mixing tube and spaced therefrom. Fitted over the outer tube 15 is a hood 16 which connects the pipes 2 leading to the burners, and which hood is formed with a downwardly projecting portion 18 above the mixing tube for the purpose of deflecting the generated gas downwardly between the mixing tube and outer tube 15 to the sub-flame openings 19. The conduit 12 leading from the bottom of the generator is formed below the pipe 13 with a closing valve 20.

The supply tank D, as shown, is preferably formed with a gage 21 to indicate the amount of liquid therein, and with an air inlet tube 22 through which air may be pumped to allow air pressure to be kept upon the contained hydro-carbon. The air inlet tube 22 has a suitable closing valve 23 and on the inner side of the valve an indicator 24 to show the air pressure. The filling tank is supplied with an inlet opening closed by a suitable cap 25.

I show, in connection with my stove, a suitable mantle burner F supported upon a generator corresponding in construction to the generator C except that in connection with the mantle burner I show one generating chamber surrounding the mixing tube instead of two. The mantle burner F is supported upon a pipe 30 extending downwardly through the top of the reservoir D and substantially to the bottom thereof. The pipe 30 is shown provided with a suitable closing valve 26.

In use, the liquid hydro-carbon, is supplied through the tank E. With the valves 5 and 20 open, the liquid will pass by grav-

ity from the tank E through the generator and pipe 4 to the tank D, causing a flushing out and cleaning of the generator. After the tank E is emptied through the generator to the supply tank D, the valve 20 will be closed and remain closed during the process of generating the gas. The supply tank D being filled in the manner set forth, air can be pumped upon the liquid within the tank through the pipe 22 to maintain the requisite pressure upon the hydro-carbon liquid and cause it to be properly fed to the generator. After the use of the range is completed and the gas turned off, the opening of the valve 20 with the valve 5 open will cause the hydro-carbon liquid within the supply tank D to be forced by the compressed air above it through the pipe 4, generator and pipe 13 to the filling tank E. The passing of the cold liquid back through the generator to the filling tank will immediately cool the generator, cleaning the same and preventing the ordinary boiling down and depositing of hard carbon in the passages of the generator. Similarly the opening of the corresponding valve 20 in connection with the burner F will allow the cool liquid to flow back through the generator of the light F to the filling tank E. The cap 25 of the filling tank is loose enough so that the compressed air passing back from the supply tank will escape from the filling tank. Thus the hydro-carbon liquid as soon as it is all forced back to the filling tank will begin by gravity to run back to the supply tank. It is thus easy with my apparatus to keep the generator clean, in addition to quickly cooling it off in the cleaning process, after use, to prevent the ill effects arising from the ordinary slow cooling. After the use of the range is completed and the liquid hydro-carbon forced back into the filling tank, it will, as stated, immediately run back to the supply tank through the generator, so that when it is desired to again use the range it is only necessary to close the valve 20 and pump

air upon the liquid hydro-carbon in the supply tank.

My features of invention are equally applicable to generators for the purpose shown and described or to generators used for kindred purposes as blow torches.

I claim as my invention:

1. A liquid hydro-carbon generating system of the class described comprising a generator and burner, a filling tank, a supply tank, conduits connecting said tanks through the generating chamber whereby to establish communication between said supply tank and filling tank through said generator, and means for forcing the contents of one of said tanks to the other of said tanks through said generator.

2. A liquid hydro-carbon generating system of the class described comprising a generator and burner, a filling tank, a supply tank, conduits connecting said tanks through the generating chamber whereby to establish communication between said supply tank and filling tank through said generator, and means permitting air to be compressed within said supply tank upon contained liquid hydro-carbon to force the contained supply through said generator to said filling tank.

3. A liquid hydro-carbon generating apparatus of the class described, comprising a generator and burner, a supply tank and a source of supply, means for establishing communication between the source of supply and supply tank through said generator, means for independently closing communication between said generator and said source of supply and said generator and supply tank, and means for forcing the contents of the supply tank through said generator to the source of supply.

In testimony whereof I affix my signature in presence of two witnesses.

SIMEON F. PIERCE.
